UNITED STATES PATENT OFFICE.

ALBERT ERICKSON, OF CHICAGO, ILLINOIS, ASSIGNOR TO SPLITDORF ELECTRICAL COMPANY, OF NEWARK, NEW JERSEY.

IMPULSE-STARTER COUPLING.

1,411,080.

Specification of Letters Patent. Patented Mar. 28, 1922.

Application filed April 10, 1918. Serial No. 227,798.

To all whom it may concern:

Be it known that I, ALBERT ERICKSON, a citizen of the United States, and a resident of Chicago, in the county of Cook and State 5 of Illinois, have invented certain new and useful Improvements in Impulse - Starter Couplings, of which the following is a specification.

My invention relates to a coupling device 10 to be used particularly with internal combustion engines, which when being started have a relatively low rotative speed at a time when the engine is going over compression, which is in general the proper time for 15 firing the gases in the engine cylinder and under this condition the spark produced by the magneto is rather weak and with the poor mixture usually obtained, at this time, starting is very difficult. As soon as the 20 engine is started the magneto renders ideal ignition. In order to overcome the objection above stated it has become the practice to accelerate the rate of speed of the rotating part of the magneto regardless of the slow 25 speed of the engine crank shaft, thereby obtaining a spark substantially equivalent to the spark produced by the magneto at the normal operating speed of the engine.

In general this driving mechanism for the 30 magneto includes a coupling having a driving member connected to an operating shaft of the engine and a driven member securely fastened to the shaft of the rotating element of the magneto with an impulse spring associated between the driving and driven 35 members and brought into operation, either at the will of the operator or automatically, whereby the driven member is held from rotating until the driving member has advanced a predetermined number of degrees, when the driven member is released and the 40 impulse spring causes the driven member and the rotating part of the magneto to rotate rapidly forward thus producing a very 45 efficient spark in the engine cylinder.

It is the object of my invention to provide a device having the general characteristics above described but with certain refinements and improvements therein all of 50 which will be later pointed out.

Where the drive effort of the driving member is applied to the driven member through the impulse spring as is sometimes done, there is a tendency for the driven 55 member to lag behind the driving member

and it is another object of my invention to provide means for locking the driving and driven members securely together after the engine has been started in order to prevent this lag.

Other and further objects will be apparent after a study of the specification and drawings which form a part thereof, in which Figure 1 illustrates a magneto of a well known type having my impulse starter coupling attached to its operating shaft.

Figure 2 is a perspective view of the driving member of the coupling.

Figure 3 is a view of the driven member with the parts in substantially the same relative position as in Figure 1, but with the driving member of Figure 2 removed.

Figure 4 is a view similar to Figure 3 but with the impulse and buffer springs with their supporting plate removed and the coupling member in neutral position.

Figure 5 is a view of the plate supporting the impulse and buffer springs.

Figure 6 is a view of one of the latch coupling lock arms.

Figure 7 is a side elevation of Figure 4 looking from the lower side showing the hub of the driven member in dotted position.

Figure 8 is a view of the member used for closing the opening used for assembling 85 the latch coupling into the driven member.

Figure 9 is a view of the dust cap protector.

Figure 10 is a longitudinal sectional view through the starter coupling shown in Figure 1.

Referring now to the details, in which like numbers refer to corresponding parts in the various views, 1 is a magneto having my improved coupling mounted on its rotating member. The coupling is made up in general of a driven member 2 and a driving member 3. The driven member 2 has a hub 4 which is centrally located with reference to the side walls of the member. The hub 4 has a hole 5 preferably tapering to fit the magneto shaft and a keyway 6 to receive a key carried by the magneto shaft. The driven member 2 carries a latch coupling 7 which is clearly shown in Figure 4. The latch 7 is shown provided with two projecting ends 8 and 9 which are adapted to extend through perforations 10 in the side walls of the driven member. It is to be understood that the latch member 7 may have one or more pro-

jections to suit the conditions. It will be apparent by an inspection of Figure 4 that it is impossible to assemble the latch 7 on to the driven member 2 if only the oblong 5 holes 10, which are slightly larger than the projections 8 and 9 and of the same shape, are alone provided. In order to tilt the latch 7 sufficiently to assemble it, I have provided a further opening 11 for one of the 10 projections 8 and in order to close up this opening to keep out dust and dirt and other foreign matter I have provided a resilient member 12, shown in Figure 8, that is adapted to snap into the opening 11 thereby closing it up. The curved portions 13 of the member 12 are adapted to engage the side wall of the driven member 2. The latch 7 carries on it arms 14 and 15 which are adapted to be centrifugally operated being pivoted to the latch at 16 and 17. As shown, the arms 14 and 15 are adapted to swing outwardly beneath the latch 7 which has its central portion cut away leaving the outer part encompassing the hub 4. The arms 14 and 15, which I term locking arms, have locking fingers 18 and 19 which are adapted to engage the notches 20 and 21 cut on the outer extremity of the sleeve 22 which is a part of the driving member 3 and which is 25 adapted to fit over the hub 4, extending to and resting against the bottom of the driven member 2. The locking arms 14 and 15 have projections 23 and 24 which serve as fulcrums for the locking arms, the opposite 30 ends of which are enlarged as much as possible to supply weight at this end. The driven member 2 is preferably counterbored to a certain depth providing an annular shoulder 25 which serves to support the plate 35 40 26 which has a lug 27 adapted to project into or through the side walls of the driven member 2 whereby it is prevented from rotating by pressure applied to the pin 28 securely fastened thereto. A similar pin 29 is 45 carried on the driving member 3 which also has cams 30 and 31 formed toward the extremity of the sleeve 22. Cams 30 and 31 are adapted to engage cams 32 and 33 on the latch 7 for a purpose which will be later described.

50 As shown in Figure 3 the plate 26 is in position and supported thereon is an impulse spring 34 which abuts against the pin 28 on one side thereof and against the pin 29 when the driving member 3 is in position.

55 As shown in Figure 3 the pin 29 is shown dotted, indicating the position which it would occupy if the driving member 3 were in position. Interposed between the pins 28 and 29 is a second spring 35 which I designate as a buffer spring.

Coming now to the operation of my device, I provide on the magneto 1 a catch plate 36 having a notch 37 therein which notch is adapted to engage the projections 60 65 8 and 9 as the engine and magneto rotating

member is slowly turned, it being understood that the driving member 3, by means of the slots 38, is connected by an Oldham coupling member to a suitable driving shaft of the engine. When either of the projections 8 or 9 engages the notch 37 the driven member 2 is prevented from rotating and since at this time the locking arms 14 and 15 are in position shown in Figure 3, the locking fingers 18 and 19 are out of engagement with the notches 20 and 21 of the driving member 3, consequently the driving member 3 will move forward in the direction of the arrow thereby compressing the impulse spring 34 until one of the cams 30 or 31 engage one of the cams 32 or 33 on the latch 7, depending on which one is in position to operate. As one pair of the above cams come into engagement, the latch 7 is lifted out of the notch 37 and the driven member 2 will be released and driven rapidly forward, due to the stress put on the impulse spring 34, thereby moving the rotating element of the magneto rapidly and producing a hot spark. When the driven member has reached its full forward position, by the impulse of the spring 34, the shock produced by it suddenly catching up with the driving member is absorbed by the buffer spring 35. Assuming that the engine starts on the first explosion of gas and rapidly comes up to speed, the arms 14 and 15 being acted on by centrifugal force and working on the projections 23 and 24 as fulcrums against the inner wall of the driven member 2, it will be seen that the latch 7 will be centralized and held in the neutral position whereby the projections 8 and 9 will clear the notch 37 as the coupling rotates. At the same time the locking fingers 18 and 19 will engage the notches 20 and 21 thereby locking the members 2 and 3 together so that the driving power of the driving member is not transmitted to the driven member 2 through the impulse spring 34 and hence all lag is avoided between the driving and driven members at the normal running position of the engine. Should, for any reason, the engine be slowed down to a point where the ignition generator would not be efficient then it will be seen that the centrifugally operated arms 14 and 15 will move toward the hub 4 and unlock the driving and driven members 2 and 3 allowing the reciprocating latch 7 to come into operation thereby giving a hot spark.

In order to render the coupling as dust proof as possible I provide a dust cap 39 which is adapted to fit over the flange 40 of the driving member 3 which in turn is adapted to come flush with the rim 41 of the driven member 2 when the driving and driven members 2 and 3 are in assembled position.

In my application Serial No. 182,729 filed July 23, 1917, I have shown and described a coupling device of which the present application is an improvement, and it will 5 be understood that numerous changes and alterations may be made in the details of the various parts of my coupling device without departing from the spirit of my invention and the scope of the appended 10 claims.

Having thus described my invention what I claim is:—

1. An impulse starter coupling for an electrical current generator, comprising a 15 driven member adapted to be secured to the rotating part of the generator, a driving member rotatably mounted on the driven member, a reciprocating latch plate permanently engaging with the driven 20 member, and having one or more parts adapted to project beyond its periphery thereof when the latch plate is reciprocated to the end of its motion in that direction, 25 means for engaging the said projecting part, an impulse spring, a support plate for said spring, means supported wholly by said support plate and cooperating means on the driving member for setting the spring at tension by rotating the driving member in 30 advance of the driven member, and cooperating means on the latch plate and on the driving member for moving the latch plate to withdraw the said projection from its 35 engaging means to release the driven member, after the spring is set at tension.

2. An impulse starter coupling for an electrical current generator, comprising a driven member adapted to be secured to the rotating part of the generator, a driving 40 member having cams rotatably mounted on the driven member, a latch plate carried by the driven member and having centrifugally controlled member attached thereto, said latch plate being adapted to 45 be reciprocated alternately by gravity and by said cams assisted by the centrifugally controlled members, said latch plate having one or more parts adapted to project beyond the periphery of the driven 50 member when the latch plate is moved by gravity, means for engaging the said projecting part, a spring connecting the driven and driving member and adapted to be 55 set at tension by rotating the driving member in advance of the driven member, and means on the latch plate adapted to co-operate with the cams on the driving member to raise the latch plate to withdraw the projecting part from its 60 engaging means whereby said driven member is moved rapidly forward by the tension of said spring and means carried by said centrifugally controlled members on the latch plate for taking the driving force

of the driving member after a predetermined speed has been reached. 65

3. The combination with a driven member secured to the rotating part of an electrical current generator, a rotatable driving member carrying a pin thereon, a spring support plate having a pin integral therewith, 70 said plate being carried by the driven member in such a manner as to prevent relative rotation between the two, and a spring carried on said support plate having one end 75 abutting against said pin and its other end abutting against said pin on the driving member so as to be tensioned by rotating the driving member in advance of the driven member, of a coupling device permanently 80 engaging with the driven member and having pivoted locking arms adapted to be brought automatically into engagement with the driving member when the driving member is rotated to a predetermined point in 85 advance of the driven member, said pivoted locking arms having locking fingers for engaging with the driving member while the generator is driven at or above its normal speed, as and for the purpose described. 90

4. An impulse starter coupling for an electrical current generator, comprising a centrifugal casing having a hub adapted to be secured to the rotating part of the generator, a coupling member adapted to fit 95 within said casing and having a part fitting over said hub and rotatable relatively thereto, a radial oscillating latch plate mounted in the casing and revolving therewith and having locking arms adapted to engage positively with the coupling member when said arms are at their substantial limit of the motion caused by centrifugal force, a catch adapted to engage the latch plate and hold it and the casing against rotation when the 100 casing and latch plate are turned very slowly; a spring yieldingly connecting the casing and coupling member, a cam on the latch plate and a cooperating cam on the coupling member adapted to move the coupling member to disengage it from said catch and thereby assisting the locking arms to move the latch plate into neutral position whereby they engage said coupling when the spring is set at tension by rotating the 105 coupling member forward relative to the casing. 110

5. An impulse starter coupling for an electrical current generator, comprising a casing adapted to be secured to the rotating part of 120 the generator; a coupling member positioned in rotatable relation to the casing, a radial oscillating latch plate revolving with the casing and having locking arms adapted to engage with the coupling member when the 125 arms are at the limit of their motion caused by centrifugal force, a catch adapted to intercept and hold the latch and the casing

from rotating when the latch is at the lower limit of its motion, cam members on the coupling member and on the latch plate adapted to move the latch plate into a position releasing it and the casing from the catch, and a spring resisting rotary movement of the coupling member relative to the latch plate to the cam releasing position and then adapted to drive the casing forward 10 and a second spring adapted to receive the blow of the forward movement of said casing.

6. In an impulse starter coupling for an electrical current generator, comprising a 15 casing adapted to be secured to the rotatable part of the generator; a coupling member rotatable relative to the casing, a radial oscillating latch plate having two parts adapted to project through the casing, 20 said casing being cut away below one of said projecting parts whereby said latch plate may be assembled within the casing and means for closing said cut-away portion after the latch plate is assembled with- 25 in the casing, centrifugally operable members pivoted to said latch plate for holding the same in neutral position, said members at the same time engaging the coupling member to take the drive between the coupling member and the casing; a catch adapted 30 to intercept and hold the latch plate and the casing and preventing it from rotating when the catch plate is at the lower limit of its motion, cooperating means on 35 the coupling member and latch plate for moving the latch plate into a position to release it and the casing from said catch and a spring tensioned by the coupling member during the interval that the casing is 40 held from rotation for causing the casing to advance rapidly forward when released and a second spring adapted to absorb the shock of the forward movement of said casing, as and for the purpose described.

45 7. A starter coupling for igniter magnetos comprising coaxial, relatively rotatable driving and driven members, a lock for connecting said members to positively hold the same against relative rotation and made operative at a predetermined speed of the coupling member; said lock consisting of, a reciprocating latch plate supported by the driven member and carrying centrifugally controlled members having locking fingers, and 50 notches in a part of the driving member adapted to be engaged by said locking fingers; an actuating spring interposed between said members, a catch arranged to successively arrest said driven member to thereby 55 place said spring under tension and means for automatically releasing the driven member from said catch.

8. A starter coupling for igniter magnetos comprising coaxial, relatively rotatable driving and driven members, a lock for connect-

ing said members to positively hold the same against relative rotation and made operative at a predetermined speed of the coupling member; said lock consisting of, a reciprocating latch plate supported by the driven member and carrying centrifugally controlled members having locking fingers, and notches in a part of the driving member adapted to be engaged by said locking fingers; an actuating spring interposed between 75 said members, said latch plate having one or more parts projecting through the wall of the driven member, a catch arranged to successively engage the projecting part or parts of said latch plate to arrest said driven member to thereby place said spring under tension and means consisting of co-operating cams on the latch plate and driving member for automatically releasing the latch and driven member from said catch. 85

9. In an impulse starter coupling for igniter magnetos, the combination of, a driven member; having a centrally located hub adapted to be fastened to the magneto shaft, a reciprocating latch carried by the 90 driven member having one or more cam surfaces and at least one part adapted to project through the side wall of the driven member, centrifugally controlled members pivoted on said latch and adapted to assist 95 in moving the latch to, and holding it in, a neutral position, a plate carrying a pin and supported by the side wall of the driven member and having a lug projecting there- 100 through; and a driving member having a centrally located sleeve fitting over the hub on the driven member and abutting against the bottom of the driven member, one or more cams on said sleeve adapted to engage the cam or cams on said latch during the 105 starting interval, a pin on the driving member; a buffer spring supported on said plate between said two pins and an impulse spring carried on said plate and abutting against the opposite sides of said pins from the 110 buffer spring and a catch for engaging that part of the latch which protrudes through the wall of the driven member when the same is at rest or turning slowly, whereby the driven member is held for a predetermined 115 interval and the impulse spring put under stress which drives the driven member rapidly forward when it is released by the cam or cams on the driving member acting on the cam or cams on said latch. 120

10. In an impulse starter coupling for igniter magnetos the combination of, a driven member; having a centrally located hub adapted to be fastened to the magneto shaft, a reciprocating latch carried by the 125 driven member and encompassing said hub, centrifugally controlled members pivoted to said latch for holding and moving the same as described, a plate supported by the side wall of the driven member and having a 130

lug projecting through the side wall thereof and carrying a stop pin, and a driving member having a centrally located sleeve adapted to fit over said hub on the driven member, 5 cams on said sleeve for engaging said latch, a pin carried on the body part of the driving member and an impulse spring supported by said plate interposed between said two pins and means for engaging the ends of said

latch whereby the driven member is prevented from rotation over a predetermined angle until released by said cams acting on the latch and whereby the impulse spring is compressed to suddenly drive the driven member forward when it is released. 10

15 In witness whereof, I affix my signature.

ALBERT ERICKSON.
